CLAIM

The ornamental design for a shoe, as shown and described.

DESCRIPTION

FIG. 1 is a rear perspective view of a shoe showing my new design;

FIG. 2 is a front perspective view thereof;

FIG. 3 is an opposite rear perspective view thereof;

FIG. 4 is an opposite front perspective view thereof;

FIG. 5 is a side view thereof;

FIG. 6 is a rear view thereof; and,

FIG. 7 is an opposite side view thereof.

The broken lines immediately adjacent to the shaded areas on the heel region define the internal bounds of the claimed design and form no part thereof. The V-shaped broken line within the shaded area of the midsole region in FIGS. 3-5 show a feature that forms no part of the claimed design. The broken lines depicting the remainder of the shoe show features that form no part of the claimed design.
